UNITED STATES PATENT OFFICE.

WILLIAM A. TURBAYNE, OF NIAGARA FALLS, NEW YORK, ASSIGNOR TO U. S. LIGHT & HEAT CORPORATION, OF NIAGARA FALLS, NEW YORK, A CORPORATION OF NEW YORK.

LAMP-VOLTAGE REGULATOR.

1,320,995.

Specification of Letters Patent.

Patented Nov. 4, 1919.

Application filed July 18, 1917. Serial No. 181,397.

To all whom it may concern:

Be it known that I, WILLIAM A. TURBAYNE, a citizen of the United States, residing at Niagara Falls, in the county of Niagara 5 and State of New York, have invented new and useful Improvements in Lamp-Voltage Regulators, of which the following is a specification.

The present invention relates to lamp voltage regulators.

More particularly the present invention relates to improved regulating means adapted to be inserted between the storage battery and translating devices in a system having a 15 variable voltage source, as for instance, a car-lighting system. A great deal of difficulty has been experienced with lamp voltage regulators in use in car-lighting systems, for the reason that they are called upon to take 20 care of wide variations in the supply voltage and wide variations in the lamp load. For instance, a heavy load may be used when the generator is inoperative. At this time the resistance of the lamp regulator 25 should be very small. At other times a low lamp load is used when the voltage across the terminals of the storage battery is high. At such times it is necessary that the lamp voltage regulator have a considerable resistance.

An object of the present invention is to provide a lamp voltage regulator having a maximum range and involving only simple mechanism.

A further object is to provide a lamp voltage regulator which will provide close regulation over a wide range.

A further object is to provide a lamp voltage regulator of the compressible pile type in which a plurality of piles are provided and through which the paths of the electric current may be charged to suit the necessities at the various stages over a wide range of regulation.

Further objects will be apparent as the description proceeds.

Referring to the drawings:

Figure 1 represents diagrammatically one embodiment of the present invention.

Fig. 2 represents a modification.

Figs. 3, 4 and 5 represent the carbon piles of the systems disclosed in Figs. 1 and 2 at different stages of operation.

Fig. 6 represents a modified switching

mechanism which may be applied to either Fig. 1 or Fig. 2.

The numerals 1 and 2 represent conductors which may be connected to a variable voltage source, such for instance, as a generator driven from the car axle. Across the conductors 1 and 2 are connected a storage battery 3 and a lamp circuit 4, containing lamps 4^a. Connected in the lamp circuit 4 is a rheostat comprising a pair of compressible piles 5 and 6. A solenoid 7 is also connected in said circuit. A voltage-responsive solenoid 8 is connected across the lamp circuit through an adjustable resistance 9. The compressible piles 5 and 6 should preferably be of the same dimensions and should be arranged with their axes substantially parallel. Two compressible piles have been illustrated. The invention is also adaptable to systems using a single pile or three or more piles. Adjacent ends of the compressible piles 5 and 6 may be relatively fixed. A yoke 10 is adapted to operate on the other ends of said piles 5 and 6 for the purpose of exerting pressure thereon. Movement of said yoke is controlled by the lever 11, pivoted at the point 11^a. This lever 11 is controlled by the bell crank lever 12, pivoted at the point 13 and controlled by the voltage-responsive solenoid 8. Preferably a pivoted connection will be provided between the lever 11 and the yoke 10 whereby a rocking movement of the yoke 10 will be permitted to compensate for differences in the mechanical construction of the piles 5 and 6 which will be encountered in practice.

As will be apparent from an inspection of Fig. 1, one end of the pile 5 is connected to the conductor 1. The adjacent end of the pile 6 is connected through the solenoid 7 and lamps to the conductor 2. The other ends of the piles 5 and 6 are connected together through a conductor of low resistance. A mid point 14 of the pile 5 is connected through a conductor of low resistance to the switch contact 15. A mid point 16 of the pile 6 is connected through a conductor of low resistance to the switch contact 17. The ends of the piles 5 and 6, distant from the yoke 10, are connected respectively to the switch contacts 18 and 19. Contact 20 is adapted to bridge contacts 17 and 18 while contact 21 is adapted to bridge contacts 15 and 19 under predetermined conditions.

The mid points 14 and 16 may be chosen as desired but are illustrated as being placed one-third of the length of the piles distant from the ends adjacent the yoke 10.

5 The solenoid 7 is adapted to control a bell crank lever 22. The contacts 20 and 21 are mounted upon said bell crank lever 22 but are insulated therefrom and from each other. Said bell crank lever 22 is normally 10 biased by a spring 23 to maintain contacts 20 and 21 out of contact with their complementary contacts. Contacts 15 and 19 are spaced in advance of contacts 17 and 18, whereby, when solenoid 7 is energized to a 15 predetermined degree, the bell crank lever 22 will be moved to cause the bridging of said contacts 15 and 19. Upon further predetermined excitation of solenoid 7, the bell crank lever 22 will be further moved to cause 20 the bridging of contacts 17 and 18, the bridging of contacts 15 and 19 being also maintained.

A mode of operation of the embodiment of the present invention illustrated in Fig. 1, is substantially as follows: If no lamp load, 25 or a lamp load of low value is being used, the bell crank lever 22 will be in the position illustrated, whereby bridging contacts 20 and 21 are out of contact with their complementary contacts. Carbon piles 5 and 6 30 will be connected in series at this time. Upon any tendency of the voltage across the lamp circuit to vary from a predetermined value, the solenoid 8 will operate through bell crank lever 12 and lever 11 35 to vary the resistance of said piles 5 and 6 to bring said voltage back to the desired value. When a predetermined lamp load is being used, the solenoid 7 will be sufficiently energized to move the bell crank 40 lever against the tension of the spring 23, whereby contact 21 will bridge contacts 15 and 19. Circuit through the rheostat is thereby varied, whereby circuit may be 45 traced from the conductor 1 through the pile 5 to mid-point 14, to switch contacts 15, 21, 19, through solenoid 7, to conductor 2. The effective resistance of the rheostat is thereby materially reduced. Upon a further lamp load of a predetermined value 50 being taken, solenoid 7 will move bell crank lever 22 to cause the bridging of contacts 17 and 18. At this time three parallel circuits through piles 5 and 6 are provided 55 whereby, for any given stage of compression, the resistance of the rheostat will be a minimum.

By referring to Figs. 3 and 4, the change 60 in the circuits through the piles 5 and 6 will be made more apparent. For the purpose of illustration, each of the piles 5 and 6 has been arbitrarily given a resistance value, under maximum compression, of .03 of an ohm, which is a value chosen from 65 practice. Under the conditions illustrated

in Fig. 3, i. e., before contact 20 has been moved to contact-making position, the resistance of the piles 5 and 6 will be $.03 + .03 = .06$ ohms. Considering a lamp load of 50 amperes which is a value chosen 70 from practice, the E. M. F. drop across the regulator would be $.06 \times 50$, or 3 volts.

Considering conditions represented in Fig. 4; i. e., after both contacts 20 and 21 have been moved to contact-making position, it will be apparent that the resistance 75 of the regulator will be

$$R = \frac{1}{\frac{1}{.02} + \frac{1}{.02} + \frac{1}{.02}} = .0066 \text{ ohms.} \quad 80$$

With a 50 ampere lamp load, the E. M. F. drop will be—

$$E = .0066 \times 50 = .34 \text{ volts.} \quad 85$$

It will thus be apparent that a greatly reduced voltage drop is produced under conditions of heavy load by the use of the present invention.

The modified system illustrated in Fig. 2 will now be described. In Fig. 2, the mechanism operated by solenoids 7 and 8 is the same as that illustrated in Fig. 1. However, the connections of the piles 5 and 6 are 90 slightly different. In Fig. 2 a mid-point 24 of the piles is connected to a similarly placed mid-point 25 of the pile 6. Also a mid-point 26 of the pile 5 is connected to a similarly placed mid-point 27 of the pile 6. Adjacent ends of the piles 5 and 6 are 95 connected together. The end of the pile 5 adjacent the yoke 10 is connected to the conductor 1 and to the contact 18. The end of the pile 6 distant from the yoke 10 is connected to the solenoid 7 and to the contact 19. Mid-points 26 and 27 are connected through a low resistance conductor to the contact 15. Mid-points 24 and 25 are connected through a low resistance conductor 100 to the contact 17. 110

Before the contact 21 has been moved to contact-making position, the piles 5 and 6 will be connected in parallel. In order that the resistance of the regulator under maximum pressure may be the same as the regulator illustrated in Fig. 1, each of the sections into which the mid-points 24, 25, 26 and 27 divide the piles, may be given a resistance of .04 of an ohm under maximum pressure. Before the contact 21 has been moved to contact making position, therefore, the total resistance of the rheostat will be .06 ohms. With a 50 ampere lamp load 120 the voltage drop would be—

$$E = .06 \times 50 = 3 \text{ volts.} \quad 125$$

According to the present invention, however, after contact 21 has been moved to contact-making position, circuit may be 130

traced from conductor 1 to conductor 2 through two parallel paths, to wit, from conductor 1 through piles 5 and 6 in parallel to mid-points 26 and 27 to contacts 15, 21 5 and 19, through solenoid 7 to conductor 2. The effective resistance of the rheostat will

thus be materially reduced. After both contacts 20 and 21 have been moved to contact-making position, six parallel paths through piles 5 and 6 will be provided, 10 whereby the resistance of the regulator under maximum compression will be—

$$R = \frac{1}{\frac{1}{.04} + \frac{1}{.04} + \frac{1}{.04} + \frac{1}{.04}} = .0066 \text{ ohms.}$$

With a 50 ampere lamp load, the voltage drop will be—

15 $E = .0066 \times 50 = .34 \text{ volts.}$

The progressive switching action of contacts 20 and 21 will insure that flickering of the lamps will not occur.

20 It will be obvious that the number of divisions into which the piles 5 and 6 are divided may be increased as much as desired, to increase the number of parallel paths through the piles.

25 Fig. 6 represents a modified switching mechanism which may be used in either of the arrangements illustrated in Figs. 1 and 2. In this modified mechanism, two solenoids 7^a and 7^b are used instead of the single solenoid 7. Solenoid 7^a controls the bell crank lever 22^a, while solenoid 7^b controls bell crank levers 22^b. Lever 22^a carries contact 21, adapted to bridge contacts 15 and 19, while lever 22^b carries contact 20. Levers 22^a and 22^b are held out of contact-making position by the springs 23^a and 23^b respectively. Current in the translation circuit will divide through solenoids 7^a and 7^b. By adjusting the tension of springs 23^a and 23^b, the proper sequence of action of switch contacts 20 and 21 may be secured. The various elements will be connected in circuit as illustrated either in Fig. 1 or Fig. 2.

One embodiment of the present invention 45 has been described in detail. Many modifications will occur to those skilled in the art. It is intended that this patent shall cover all such modifications that come within the scope of the invention as defined by 50 the appended claims.

What I claim as new and desire to secure by Letters Patent of the United States is—

1. In regulating means, in combination, a compressible rheostat comprising a plurality of plates in series, pressure means co-operating therewith, and load responsive means for varying the number of circuits through said plates.

2. In combination, electric mains, a translation circuit connected across said mains, said translation circuit including a compressible rheostat comprising a plurality of plates in series, said translation circuit also including electro-magnetic means for varying the current paths through said plates in successive steps.

3. In combination, electric mains, a translation circuit connected across said mains, said translation circuit including a compressible rheostat comprising a plurality of 70 plates in series, switching means connected to intermediate points of said rheostat, and means responsive to the current in said circuit for operating said switching means to vary the current paths through said plates. 75

4. In combination, in a translation circuit, a pair of compressible piles, each adapted to provide a single operative path for current throughout its length, and means responsive to the current flowing in 80 said circuit for providing parallel paths through each of said piles.

5. In regulating means, in combination, a compressible rheostat comprising a plurality of plates in series, pressure means co-operating therewith, and load responsive means for progressively varying the number of circuits through said plates. 85

6. In combination, electric mains, a translation circuit connected across said mains, 90 said translation circuit including a compressible rheostat comprising a plurality of plates in series, said translation circuit also including electro-magnetic means for progressively varying the current paths 95 through said plates.

7. In combination, electric mains, a translation circuit connected across said mains, said translation circuit including a compressible rheostat comprising a plurality of 100 plates in series, switching means connected to intermediate points of said rheostat, and means responsive to the current in said circuit for operating said switching means to progressively vary the current paths 105 through said plates.

8. In combination, in electric regulating means, a compressible rheostat comprising a plurality of plates in series, compression means for operating same, and means operative independently of said compression means for progressively varying the net resistance of said rheostat through said plates. 110

9. In combination, a circuit to be regulated, a compressible rheostat in said circuit comprising a plurality of plates in series, voltage responsive means for operating said rheostat, a plurality of switching means connected to intermediate points of said rheostat, and means responsive to the cur- 115 120

rent flowing in said circuit for progressively closing said switching means.

10. In combination, a translation circuit, a compressible rheostat comprising a plurality of plates in series, means for compressing said rheostat to reduce the resistance of same, and means responsive to the current flow through said circuit for progressively reducing the resistance through

10 said rheostat independently of said voltage responsive means.

11. In combination, a translation circuit, a compressible rheostat comprising a plurality of plates in series, means for compressing said rheostat to reduce the resist-

ance of same, and means responsive to the current flow through said circuit for progressively varying the circuit through said plates.

12. In combination, in a circuit to be regulated, a compressible pile having a plurality of resistance elements arranged in series, means responsive to the voltage across said circuit for operating said rheostat, and means responsive to the load on said circuit 20 for forming a short circuit through certain of said elements. 25

In witness whereof, I have hereunto subscribed my name.

WILLIAM A. TURBAYNE.
